UNITED STATES PATENT OFFICE.

EUSTON E. BLACK, OF ALLIGATOR POND, JAMAICA, BRITISH WEST INDIES.

PEN-EXTRACTOR.

1,383,377.

Specification of Letters Patent.

Patented July 5, 1921.

Application filed August 17, 1920. Serial No. 404,044.

To all whom it may concern:

Be it known that I, EUSTON E. BLACK, a subject of the King of Great Britain, residing at Alligator Pond, in the county of 5 Cornwall, Jamaica, and island of British West Indies, have invented certain new and useful Improvements in Pen-Extractors, of which the following is a specification.

- This invention relates to pen extractors, 10 the primary object of which is to equip the penholder with the extracting means, the latter embracing the pen on its opposite faces to positively eject the pen at the operation of the user.
- 15 Another object of the invention is to provide an extractor which may be conveniently attached to standard penholders and which will not interfere with the use of the latter.
- The above and other objects of this invention will be in part described and in part 20 understood from the following description of the present preferred embodiment of the invention as illustrated in the accompanying drawings, wherein:
- 25 Figure 1, is a side elevational view of an extractor constructed in accordance with my invention illustrating the application of the same.

Fig. 2, is a similar view showing the extractor in longitudinal section, a portion of the penholder being broken away to disclose details.

Fig. 3, is a fragmentary rear elevational view of the extractor and penholder.

35 Fig. 4, is a cross sectional view taken on the line 4—4 of Fig. 2 and looking in the direction of the arrow.

Fig. 5, is a cross sectional view taken on the line 5—5 of Fig. 1, and looking in the 40 direction of the arrow, and

Fig. 6, is a sectional view taken on the line 6—6 of Fig. 2.

In the drawings in order to illustrate the application of my invention a penholder 7 45 is provided which has mounted therein, in the usual way, a pen 8. The pen is provided with a projection thereon, in this instance consisting of a struck up lug 9, which serves as an abutment.

50 The extractor consists of a barrel 10 preferably cylindrical in configuration, and is sleeved on the holder 7 as illustrated to advantage in Figs. 1, 2 and 3. The lower end of the barrel has a clamping lever 11 pivotally mounted therein the free end of which

is turned at right angles to provide a clamping finger 12. The lever 11 is countersunk in a corresponding recess 13 formed in the barrel, the said recess terminating short of the outer end of the barrel. The lever 11 is 60 bent outwardly at right angles, adjacent the terminus of said recess and is then extended upwardly at right angles in parallelism with the barrel 10 to provide a finger engaging portion 14.

65 In order to normally retain the lever 11 in the recess 13 a retaining ring 15 is used. The ring is split as indicated at 16 to permit movement of the lever therethrough when a new pen is to be inserted in the 70 holder.

To secure the barrel 10 against sliding movement on the penholder a hook 17 is provided, one end of which is pivotally mounted upon the flanged outer end 18 of 75 the barrel 10. The bill of the hook embraces the penholder, as shown to advantage in Fig. 5, and if desired may be seated in a corresponding groove in the penholder. A finger release 19 is formed on the bill of the hook 80 for use in an obvious manner.

In use of the device it will be understood that the pen is placed in the penholder following which the clamping lever 11 is operated into the position shown to advantage in Fig. 2. In this position the finger 12 engages the shank of the pen, but may be slidably advanced over the latter after the hook 17 has been disengaged and pressure exerted upon the abutment 20 which is 85 formed integral on the periphery of the barrel 10. Pressure is simultaneously exerted upon the outer right angled portion of the lever 11. When the lower end of the barrel comes in contact with the struck up 90 lug 9, continued exertion of pressure on the barrel will cause the pen to be extracted in an obvious manner. It will be observed that the finger 12 will prevent the pen from flexing over when the barrel contacts with 95 the lug 9. After the pen has been extracted in this way the split portion 16 of the ring 15 is brought into register with the lever 11 permitting the latter to be moved on its pivot point allowing the pen to be inserted 100 in the holder. After this has been done the lever is returned to its position in recess 13 and the ring 15 rotated.

105 Various changes may be made in this device especially in the details of construction, 110

proportion and arrangement of parts. I have above described what now seems to be the preferred form of my invention.

What I claim is:

- 5 A pen extractor including a barrel equipped with a pivotally mounted clamping lever, means mounted on the barrel to normally hold the lever from movement, means mounted on the barrel to engage the
- 10 penholder for preventing relative movement

of the barrel and holder, and means to facilitate movement of said barrel on said holder at the option of the user.

In testimony whereof I affix my signature in presence of two witnesses.

EUSTON E. BLACK.
